(57) **CLAIM**

The ornamental design for a cart handle, as shown and described.

DESCRIPTION

FIG. 1 is a perspective view of a cart handle showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 3;

FIG. 18 is a partial enlarged view of FIG. 3;

FIG. 19 is a partial enlarged view of FIG. 3;

FIG. 20 is a partial enlarged view of FIG. 4;

FIG. 21 is a partial enlarged view of FIG. 4;

FIG. 22 is a partial enlarged view of FIG. 4;

FIG. 23 is a partial enlarged view of FIG. 5;

FIG. 24 is a partial enlarged view of FIG. 5;

FIG. 25 is a partial enlarged view of FIG. 5;

FIG. 26 is a partial enlarged view of FIG. 6;

FIG. 27 is a partial enlarged view of FIG. 6;

FIG. 28 is a partial enlarged view of FIG. 6;

FIG. 29 is a partial enlarged view of FIG. 7;

FIG. 30 is a partial enlarged view of FIG. 7;

FIG. 31 is a partial enlarged view of FIG. 8; and,

FIG. 32 is a partial enlarged view of FIG. 8.

The shorter broken lines in the figures show portions of the cart handle which form no part of the claimed design. The longer broken lines in the figures shown enlarged areas in the figures.
